UNITED STATES PATENT OFFICE.

FRANK C. STUCKEL, OF RACINE, WISCONSIN, ASSIGNOR TO UNIVERSAL FASTENING CO., OF RACINE, WISCONSIN, A CORPORATION.

RAIL-ANCHOR.

1,159,430.

Specification of Letters Patent. Patented Nov. 9, 1915.

Application filed December 14, 1914. Serial No. 877,087.

To all whom it may concern:

Be it known that I, FRANK C. STUCKEL, a citizen of the United States, and a resident of Racine, county of Racine, and State 5 of Wisconsin, have invented certain new and useful Improvements in Rail-Anchors, of which the following is a full, clear, and complete description.

The invention relates to anchors or anti-creepers for railway rails and seeks to provide a simple, inexpensive construction which can be readily and securely fastened to the rail and which is not solely dependent upon a frictional grip for holding it in 15 place.

The invention consists in the features of improvement hereinafter set forth illustrated in the preferred form in the accompanying drawings and more particularly 20 pointed out in the appended claims.

In the drawings, Figure 1 is a plan view of a portion of a railway rail and tie with the improved anchor applied thereto. Fig. 2 is an elevation of the same. Fig. 3 is a 25 detailed section on the line 3-3 of Fig. 2, and Fig. 4 is a detailed section on the line 4-4 of Fig. 1.

The improved rail anchor comprises a transverse member or bar 10 adapted to extend beneath the rail 11 and having means, such as a clip or clips 12, at one end for engaging one of the base flanges of the rail and a jaw 13 at its opposite end for receiving the other base flange. These parts are 35 preferably formed of an integral malleable casting, and the transverse bar or member 10 is provided at one edge with an integral depending tie-abutting portion or flange 14 which is of greatest width opposite the jaw 40 13, as shown in Fig. 2.

The transverse bar or member 10 in the form shown extends substantially at right angles to the rail 11, and two rail-engaging clips 12 are preferably provided at one end 45 of the bar. Before the anchor is installed in position upon the rail these clips are vertically disposed as indicated in dotted lines in Fig. 2. The anchor is placed in position upon the base of the rail with the tie-abutting portion or flange 14 against the tie 15 and the clips 12 are bent down to snugly engage one of the base flanges of the rail and at the same time draw the jaw 13 snugly into 50 engagement with the other base flange.

Preferably as shown, the end of the trans- 55 verse member which is provided with the clips 12 is also provided with a horizontal flange 16 which is adapted to overlap the upper face of the tie.

Rail anchors usually depend upon a friction grip for preventing the creeping of the rail. In accordance with the present invention, means is provided for positively locking the anchor to the rail. For this purpose the jaw 13 is provided with a vertical opening or socket 17, and a fastening key 18 fitting within the socket is adapted to cut into the base flange of the rail to secure the anchor thereto. The socket, as shown, is preferably square and is angularly 70 disposed so that its inner corner intersects the flange receiving opening of the jaw. To form an extended bearing or support for the fastening key 18, the vertical socket 17 is formed within thickened portions or bosses 75 19 and 20 upon the upper and lower walls of the jaw 13. In the preferred construction shown, a bracing flange 21 extends between the tie-abutting flange 14 and the lower thickened portion or boss 20, and this 80 bracing flange is provided with a shoulder 22 beneath the socket which serves as a stop for the fastener key 18.

The fastener key 18 is formed of hardened steel, is square in section as shown, and is 85 adapted to snugly fit within the socket 17. After the anchor is applied as above described, the fastening key 18 is driven into the socket and inasmuch as the inner portion or corner thereof intersects the flange-receiving opening of the jaw, the key cuts into or cuts away a portion of the base flange and when driven home to the position shown in the drawings positively locks the anchor upon the rail. The key and socket 90 thus form in effect male and female dies for punching and cutting out a portion of the base flange of the rail. The walls of the socket formed by the thickened portions or bosses 19 or 20 surround or entirely inclose 100 the socket and the fastening key snugly fits therein so that it cannot jar loose. Moreover, because of the angular form of the key and socket the thrust due to the creeping action of the rail will tend to turn the key and thus produce a secure binding grip between the fastening key and the walls of the socket. The key serves to positively lock 105

the anchor to the rail and the latter is thereby held against creeping.

It is obvious that numerous changes may be made in the details set forth without departing from the essentials of the invention as defined in the claims.

I claim as my invention:—

1. A one piece rail anchor comprising a transverse member adapted to extend beneath the base of the rail and having an integral tie-abutting portion, an integral part or parts for engaging one of the base flanges of the rail and an integral jaw overlapping and engaging the other base flange, said jaw having a vertical socket intersecting the rail receiving opening thereof, and a fastening key adapted to be driven through said socket and having a sharpened inner edge adapted to cut into the base flange of the rail to secure the anchor thereto.
2. A rail anchor comprising a transverse member having means for engaging one of the base flanges of the rail and a jaw for receiving the other base flange, said jaw having a vertical inclosed socket the inner portion of which intersects the jaw opening, and a fastening key fitting said socket and adapted to cut into the base flange of the rail to secure the anchor thereto.
3. A rail anchor comprising a transverse member having means for engaging one of the base flanges of the rail and a jaw for receiving the other base flange, said jaw having a vertical angular socket the inner corner of which intersects the jaw opening, and an angular fastening key fitting said socket and adapted to cut into the base flange of the rail to secure the anchor thereto.
4. A rail anchor comprising a tie-abutting portion and a transverse member having means for engaging one of the base flanges of the rail and a jaw for receiving the opposite base flange, said jaw having a vertical socket intersecting the jaw opening, and a hardened fastening key fitting said socket and adapted to cut away a portion of the

base flange of the rail to positively lock the rail anchor thereto.

5. A rail anchor comprising a tie-abutting portion and a transverse member having means for engaging one of the base flanges of the rail and a jaw for receiving the opposite base flange, said jaw having thickened walls and a vertical inclosed socket the inner portion of which intersects the jaw opening, and a hardened fastening key fitting said socket and adapted to cut away a portion of the base flange of the rail to positively lock the rail anchor thereto. 60 55 60

6. A rail anchor comprising a transverse member having an integral tie-abutting portion and having a clip and a jaw integral therewith for engaging the base flanges of the rail, said jaw having a vertical socket 65 intersecting the jaw opening and a hardened fastener key fitting said socket and adapted to cut away a portion of the base flange of the rail.

7. A rail anchor comprising a transverse member having an integral tie-abutting portion and having a clip and jaw integral therewith for engaging the base flanges of the rail, said jaw having thickened walls and a vertical socket the inner portion of 70 75 which intersects the jaw opening, and a hardened fastening key fitting said socket and adapted to cut into the base flange of the rail.

8. A rail anchor comprising a transverse member having an integral tie-abutting portion, and having integral bendable clips and a jaw for engaging the base flanges of the rail, said jaw having thickened walls and an angular socket, the inner corner of which intersects the jaw opening, and a hardened, angular fastening key fitting said socket and adapted to cut away a portion of the base flange of the rail. 80 85
